UNITED STATES PATENT OFFICE

JOSEPH ERRET, OF CLEVELAND, OHIO.

VEHICLE-STEP.

No. 810,199.

Specification of Letters Patent.

Patented Jan. 16, 1906.

Application filed May 15, 1905. Serial No. 260,430.

To all whom it may concern:

Be it known that I, JOSEPH ERRET, of Cleveland, Cuyahoga county, Ohio, have invented a new and useful Vehicle-Step, of which the following is a full, clear, and exact description, reference being had to the accompanying drawings, forming part of this specification, in which—

Figure 1 is a top plan view of my improved step in position, and Fig. 2 is a sectional side elevation of the same.

My invention relates to the class of vehicle-steps, and is designed to cheapen and improve their structure, more especially the means for clamping them to the support.

Heretofore the shanks of such steps have been forged, a clip being forged integral therewith and arranged to embrace the shaft or support to which the step is fixed.

My invention consists in making the clip separate from the step-shank and interfitting them, so that the step-shank may be cast, if desired, thus cheapening the construction.

In the drawings, 2 represents the step, and 3 the curved shank, having an upwardly-recessed head 4. This head is provided with a curved recess on its top, the inner portion of which leads into a vertical hole 5, extending down through the juncture of the head and step-shank, as shown in Fig. 2. The curved top recess and hole are shaped to receive the clip 6, which has legs 7 to embrace the axle and axle-bed 8 and 9 or other support.

In order to hold the head or base of the

step-shank more firmly in place, I may provide 35 a transverse ridge portion 10, as shown in Fig. 2, which will be drawn down into the axle-bed when the legs of the clip are drawn down by the bolts 11 bearing against the clip-bar 12.

I have shown the thin side portions of the 40 head as extending down to a level underneath and at the sides of the U-shaped clip; but it will be understood that these portions may be of varying length, and the interfitting of the clip and shank-head may be carried out in other ways without departing 45 from my invention.

The advantages of the invention lie in the cheapness of construction, since step, shank, and head may be cast and the wrought clip 50 applied thereto, and also from the neatness of appearance and strength of the structure.

Many variations may be made in the form and arrangement of the parts without departing 55 from my invention.

I claim—

The combination of a step-shank having an upwardly-recessed arch-shaped head, adapted to span the upper portion of an axle, and a separate clip extending through the recess and 60 embracing said head and axle and arranged to secure the step-shank in place on a support.

In testimony whereof I have hereunto set my hand.

JOSEPH ERRET.
